UNITED STATES PATENT OFFICE.

WILLIAM E. SHERBONDY, OF CLEVELAND, OHIO, ASSIGNOR, BY MESNE ASSIGNMENTS, TO THE BIGSBY ROTARY MANUFACTURING COMPANY, OF CLEVELAND, OHIO, A CORPORATION OF OHIO.

SPARK-PLUG.

1,173,541.

Specification of Letters Patent. Patented Feb. 29, 1916.

Application filed April 7, 1913. Serial No. 759,329.

To all whom it may concern:

Be it known that I, WILLIAM E. SHERBONDY, a citizen of the United States, and resident of Cleveland, in the county of 5 Cuyahoga and State of Ohio, have invented certain new and useful Improvements in Spark-Plugs, of which I hereby declare the following to be a full, clear, and exact description, such as will enable others skilled 10 in the art to which it appertains to make and use the same.

The objects of the invention are to provide a simple and efficient and positively acting means for preventing the deposit and 15 spreading of carbon or other conducting materials over the surface of the shell of a spark plug, where it is exposed to the products of combustion within the cylinder of an explosion engine. This deposit is 20 often made to such an extent as to provide a conductor for the electric current between the central electrode and shell, and thereby forms a short circuit of low resistance through which the electric current will 25 travel in preference to traversing the air gap between the electrodes, where a greater amount of resistance will be encountered.

It is well understood that even a slight 30 deposit of carbon connecting the electrodes of a jump spark plug will lessen the efficiency of the spark, and larger accumulations will lead the current entirely away from the air gap, and no spark at all will be produced. The effect of heating the carbon film thus formed is also to increase the 35 conductivity of the film, and the compression of the vapors or charge within the cylinder serves to increase the resistance to the electric current at the air gap, and thus 40 when the engine is in use there is a constant tendency to decrease the efficiency of the spark. To overcome this depreciation in efficiency the present invention includes 45 means for providing a projecting nipple or zone about the central electrode which will automatically free itself from deposits of conducting material, and thereby prevent 50 the short circuiting of the electric current by means of conduction or arcing. This zone is obtained by means of a projecting member which will acquire a sufficiently high degree of temperature from contact with the heated products of combustion in 55 the cylinder to consume the deposits of conducting material formed by incomplete com-

bustion and so fast as they gather thereon. This conducting material consists usually of deposits of carbon and oil.

The invention in its preferred form comprises a thin annular member of porcelain, 60 steatite or other insulating and refractory material such as will be quickly heated by the exploded charge, and which projects beyond the body of the plug into the cylinder. The central electrode projects through 65 an opening provided in this member, which is made preferably of small diameter to assist in excluding the products of combustion from the inner walls of the shell. The annular member is mounted upon, and preferably integral with, a disk (which may be of porcelain), and which forms a closure for the extremity of the shell.

The invention is hereinafter further described, shown in the accompanying drawings and specifically pointed out in the claims.

In the accompanying drawings Figure 1 is a bottom view of the improved spark plug; Fig. 2 is a vertical central section of 80 the lower part thereof; Fig. 3 is a side elevation of the closure for the shell and the attached heating element or member; Fig. 4 is a side elevation thereof.

In these views A is the shell of the spark 85 plug.

B is the central insulation.

C is the central electrode, which is mounted in the central insulation B.

D is the outer electrode.

E is the air gap, in which the arc is formed.

F is the heating element which forms a zone of non conducting material and which in its preferred form comprises a thin porcelain flange or ring projecting into the cylinder and preferably mounted upon a disk f which is seated in the extremity of the shell wall. The flange incloses a central opening f' through which the central electrode C projects, leaving preferably a narrow annular space f' between the disk and electrode. This heating element F constitutes the important feature of the invention and extends into the cylinder close enough to the spark gap to become heated by contact with the heated products of combustion when the explosion takes place. This heating element is made thin enough to become quickly heated thereby. The thin edge or 110

lip acquires a sufficiently high degree of temperature to consume any deposit of oil or carbon which would otherwise be formed thereon, and so prevents the formation of a 5 conductor of the electric current leading from the central electrode to the wall of the shell.

The carbon deposit will often in practice 10 coat the remaining portions of the disk and pile upon the edge of the wall as indicated in Fig. 2 at T, but the extreme edge of the lip will be free from deposit and form a zone of non conducting material which the current cannot cross and hence the connection 15 will be broken. The amount of conducting material entering the small annular opening f' will not be sufficient to cause any material coating of the inner walls of the shell, or enough to permit a short circuit 20 to arise between the central electrode and shell, since if the annular opening f' is of the proper size the heat acquired from contact with the member F will consume the 25 deposits before they enter the recess in the end of the shell.

Having described the invention what I claim as new and desire to secure by Letters Patent is:

1. The combination with the shell and 30 electrodes of a spark plug, of an insulating refractory disk forming a closure for the extremity of said shell, said disk provided with a thin annular outwardly projecting lip or flange providing an easily heated 35 member encircling one of said electrodes.

2. In a spark plug, the combination with the shell having a recess, the central insu-

lation, the central electrode and the outer electrode, of a disk of refractory and insulating material seated in the extremity of 40 said shell, said disk provided with a thin annular lip or flange, encircling said central electrode, and projecting beyond said shell of said spark plug.

3. In a spark plug for the cylinder of an 45 explosion engine, the combination with the shell having a recess in its outer end, and central and exterior electrodes, of a closure for said recess, and an annular insulating and refractory member forming a portion of 50 said closure, and encircling said central electrode, said member projecting longitudinally of said plug into said cylinder and exposed to the heated gases in said cylinder, and providing a zone of higher temperature 55 than the body of the closure.

4. The combination with the recessed extremity of the shell of a spark plug for the cylinder of an explosion engine, and the central and outer electrodes therefor, of a closure for the recessed extremity of said plug through which said central electrode projects, an annular refractory member at the inner edge thereof, projecting into said cylinder beyond the walls of said spark plug, 60 and forming a rim extending at an angle to said closure, and encircling said central electrode.

In testimony whereof, I hereunto set my hand this 27th day of March 1913.

WILLIAM E. SHERBONDY.

In presence of—

W.M. M. MONROE,
CHAS. H. OLDS.
